UNITED STATES PATENT OFFICE.

PERRY E. BOYD, OF CANTON, GEORGIA.

COLLAPSIBLE CRATE.

No. 869,134.

Specification of Letters Patent.

Patented Oct. 22, 1907.

Application filed January 30, 1907. Serial No. 354,883.

To all whom it may concern:

Be it known that I, PERRY E. BOYD, a citizen of the United States, residing at Canton, in the county of Cherokee and State of Georgia, have invented a new 5 and useful Collapsible Crate, of which the following is a specification.

This invention relates to collapsible crates and its object is to provide a simple structure of this character all the parts of which are permanently connected and 10 which can be quickly set up or folded.

A still further object is to provide a crate with reinforcing strips which are formed integral with the hinges connecting the parts of the crate, said straps also having integral means whereby the crate can be held when 15 set up.

With these and other objects in view the invention consists of certain novel features of construction and combinations of parts which will be hereinafter more fully described and pointed out in the claims.

20 In the accompanying drawings is shown the preferred form of the invention.

In said drawings: Figure 1 is a perspective view showing the crate set up; Fig. 2 is an enlarged section on line $x-x$, Fig. 1; Fig. 3 is a horizontal section through one 25 corner of the crate showing one of the locking ears; Fig. 4 is a view showing the crate collapsed; Fig. 5 is a side elevation showing the collapsed crate folded; and Fig. 6 is a detail view of one of the end strips of the crate.

Referring to the figures by characters of reference, A 30 is the bottom panel of the crate the same being made up of parallel slats 1 connected at their ends by metallic cross straps 2 each of which has a pair of integral eyes 3 at its ends and a pair of eyes 4 extending from the outer edge of the strap near each end. A front panel B is disposed along one edge of the bottom panel and is made up of slats 5 connected at their ends by straps 6 and each of these straps has an integral eye 7 extending between the eyes 3 of one of the pairs and held thereto by a pintle 8. The other end of each strap 6 has a 35 tongue 9 extending therefrom and provided with an aperture 10. A back panel C is arranged along the opposite side of the bottom panel A and is made up of slats 11 connected at their ends by metallic straps 12. Each of these straps is provided at its ends with eyes 13 and 14 respectively, the eyes 13 being disposed between the adjoining eyes 3 of strap 2 and connected thereto by means of a pintle 15. The top panel D of the crate may be made of one or more pieces and as shown in the drawings consists of a single strip 16 having metallic straps 17 secured to the ends thereof, each strap being provided with a pair of eyes 18 and one end of which is mounted on a pintle 19 extending through the adjoining eyes 14. A tongue 20 extends from each

strap 17 and has an opening 21 adapted to receive one of the tongues 9 hereinbefore referred to.

55

Each pair of eyes 4 carries a pintle 22 on which is mounted an eye 23 formed at one end of an L-shaped strap 24. These straps are arranged in pairs and are suitably fastened to the ends of the panels E of the crate. The straps are so shaped that the end panels 60 can be folded on to the bottom of the panel A or can be swung into an upright position on the top face of said panel, as shown in Fig. 1, in which event said end panels will rest directly upon the bottom panel A by reason of the peculiar contour of the straps 24. Each 65 strap has hooks 25 formed at the outer edges thereof. These hooks overlap the side edges of the panels E and are for the purpose hereinafter set forth,

It is to be understood that when the crate herein described is collapsed the end panels E rest upon the bottom face of panel A while the front panel B rests upon the opposite face of said panel A and is overlapped by the back panel C. It will be noted that the hinge of this back panel is raised somewhat from the panel A so that the panel C can rest upon the panel D when 75 folded. The top panel is folded backward on the panel C and the entire crate can then be fastened together by a cord or in any other desired manner. One or more trays 26 can also be included in the bundle formed by the collapsed crate. When it is desired to set up the 80 crate the panels B, C and D are unfolded after which the end panels E are swung into upright positions upon the upper face of the bottom panel A. The front and rear panels B and C are also swung into upright positions and the end panels are sprung toward each other 85 so as to permit the hooks 25 to move backward beyond the inner edges of the straps 6 and 12 and to then spring forward into engagement therewith, thereby securing the end, front and back panels together. The tray 26 can be placed within the crate and can be supported 90 on a series of baskets or other receptacles therein, such as indicated by dotted lines at 27 in Fig. 2. After the crate has been filled the top panel D is swung downward so as to cause the tongues 9 to project through the openings 21 in tongues 20. Said tongues can then be 95 locked by inserting a pin 28 or any other suitable holding device through the opening 10 in each tongue 9. The parts of the crate will therefore be securely held together. By removing these pins, raising the cover D and pressing the panels E inward the parts can be 100 quickly unlocked so as to enable the crate to be folded in the manner hereinbefore described. Importance is attached to the fact that the hinges are integral with straps which extend throughout the widths of the various panels thereby dispensing with the use of cross 105 strips, although it is to be understood that if preferred

such cross strips may be used in addition to the straps. By constructing the crate in the manner described the number of parts necessary for the proper assembling and securing of the panels is reduced to the minimum.

5 What is claimed is:

1. A crate comprising a bottom panel, a top panel, and side panels, one side panel and the bottom panel being interposed between the top panel and the other side panel, straps hingeably connected at their ends and secured to the 10 respective panels, the straps of the outer side panel having integral tongues, and the straps of the top panel having apertures to receive said tongues, angular straps hinged to one longitudinal edge of each strap of the bottom panel and movable at right angles to said straps, hooks integral 15 with the angular straps and disposed to engage the straps of the side panels, and end panels secured to the angular straps.
2. A crate comprising a bottom panel, straps extending transversely thereof and secured thereto, said straps having integral laterally extending ears, angular straps pivoted to said ears and adapted to assume positions upon 20

the bottom panel and adapted to swing onto and to be limited in their movement by the bottom panel, one portion of each of said straps extending perpendicularly to the bottom panel upon reaching the limit of its movement, end 25 panels secured to the angular straps, side panels, straps thereon, and hooks integral with the angular straps and disposed to engage the straps of the side panels to hold said angular straps in perpendicular position.

3. In a crate a hinge comprising a plurality of straps 30 hingeably connected at their ends and disposed to be fastened to the bottom, side, and top panels respectively of a crate, ears extending laterally from one edge of the strap of the bottom panel, angular straps hingeably connected to the ears, and hooks integral with said angular straps and 35 disposed to engage the straps of the side panels.

In testimony that I claim the foregoing as my own, I have hereto affixed my signature in the presence of two witnesses.

PERRY E. BOYD.
